AUTOMATIC RECORD CHANGING APPARATUS

Harvey C. Habegger, Monroe, Ind., assignor to Farnsworth Television and Radio Corporation, a corporation of Delaware

Application September 29, 1941, Serial No. 412,707

17 Claims. (Cl. 274—10)

This invention relates to automatic record-changing apparatus and more particularly to an improved mechanism for supporting a stack of records and moving the supported records one at a time to a playing position.

According to conventional drop-down record-changing apparatus, records are supported above a turntable either by a plurality of peripheral supports or by a peripheral support and means on a centering pin or solely by means on a centering pin.

In drop-down record-changing apparatus where the records are supported by a plurality of peripheral supports the records are moved to playing position either by an element associated with one of the peripheral supports or by means on the centering pin or by having a plurality of knives temporarily moved between the lowermost supported record and the second lower-most supported record at their peripheral edges after which the plurality of peripheral supports temporarily move out of supporting position for permitting the lower-most supported record to drop into playing position.

In drop-down record-changing apparatus where the records are supported by a peripheral support and means on the centering spindle, the records are moved to playing position by an element associated either with a peripheral support or the centering pin. In drop-down record-changing apparatus where the records are supported solely by means on the centering pin, the records are moved to playing position by imparting a lateral movement thereto by an element associated with the centering pin.

The object of the present invention, therefore, is to provide an improved record-changing apparatus incorporating a centering pin which is adapted to support a stack of records, either warped or flat, by engaging edge portions at the centering aperture of the lower-most supported record.

Another object of the present invention is to provide an improved record-disengaging mechanism which is associated with the centering pin and which releases the supported records one at a time without imparting to the released record any lateral movement relative to the centering pin.

Another object of the present invention is to provide an improved record-disengaging mechanism associated with a centering pin which releases the supported records one at a time in such a manner that the released records fall to

playing position on the turntable in a plane substantially parallel to the turntable.

Another object of the present invention is to provide an improved record-changing and record-disengaging mechanism for a drop-down record changer in which, after all the records have been played, they may be removed from the turntable without removing the centering pin.

Another object of the present invention is to provide an improved record-changing and record-disengaging mechanism for operating upon a stack of intermixed records.

In accordance with the present invention, there is provided a record-changing apparatus which includes a centering pin with a reduced portion in the plane of a second lower-most supported record, first movable means for supporting a stack of records for engaging an edge portion at the centering aperture of the lower-most supported record, second movable means for moving the second lower-most supported record into supporting position with the reduced portion of the centering pin, cam means operatively associated with the first and second movable means for successively moving the second movable means and permitting the first movable means to move out of supporting position whereby the lower-most supported record is released from its supported position.

For a better understanding of the invention, together with other and further objects thereof, reference is made to the following description taken in connection with the accompanying drawings, and its scope and its steps will be pointed out in the appended claims.

In the accompanying drawings:

Fig. 1 is a top plan view of the record-changing apparatus in accordance with the invention showing the turntable and base plate in phantom;

Fig. 2 is a side elevation of the record-changing apparatus showing a stack of records supported over the turntable and two records on the turntable, the top one being in playing position;

Fig. 3 is a fragmentary view of the centering pin showing the means for supporting a stack of records;

Fig. 4 is a fragmentary view of the centering pin showing the means for supporting the uppermost records of a stack while the lowermost record is being released.

Figs. 5, 6 and 7 are enlarged fragmentary views of the centering pin showing various positions of the elements for supporting and releasing records.

Referring now more particularly to Figs. 1

and 2 of the drawings, the invention here illustrated shows a record-changing apparatus which includes a base plate 10, to one side of which is fixed in a suitable manner a pedestal 11, which is adapted to pivotally support a pickup arm 12 in such a manner that the pickup arm may be moved in a horizontal and vertical plane. At the free end of the pickup arm 12 there is provided a reproducer 13 with a stylus 14 for reproducing records.

A bearing element 15 rests on the base plate 10 to rotatably support a flanged tubular shaft 16 which extends above and below the base plate 10. A turntable 17 for supporting and rotating disc records 18, as shown in Fig. 2, is connected in a suitable manner to the flanged portion of the tubular shaft 16. The lower end of the tubular shaft 16 also has affixed thereto a frictional driving member 19 and the rotating member 20. The function and operation of the members 19 and 20 will be described hereafter. The driving mechanism for the turntable 17 and the tubular shaft 16 is not shown, but any suitable means may be used which is well known in the art.

Record-supporting and record-disengaging mechanism

The mechanism for supporting a stack of records 18A (Fig. 2) above the turntable 17 and for moving the records one at a time to playing position on the turntable is best illustrated in Figs. 2-7 and includes a bracket 21 affixed in a suitable manner to the bottom of the base plate 10. A tubular centering pin 22 is fixed in a suitable manner to the bracket 21, preferably by a locking nut 23. The centering pin 22 extends upwardly through the tubular shaft 16 and above the turntable 17. Near the upper end of the centering pin 22 there are provided slots 24-24, preferably diametrically opposite to each other. Near the lower end of the slots 24-24 movable members 25-25 are fixed to the centering pin 22. The members 25-25 will also be referred to herein as first movable means. At the free ends of the members 25-25 there are provided ears 26-26 for moving in the slots 24-24 from the positions shown in Figs. 3 and 5 to the positions shown in Figs. 4, 6 and 7. When the ears 26-26 are in the position shown in Figs. 3 and 5, they are adapted to support a stack of records 18A above the turntable 17 by engaging edge portions at the centering aperture of the lower-most supported record. Above the slots 24-24 and on one side of the centering pin 22 there is provided a notch or reduced portion 27 in the plane of the second lower-most supported record. The centering pin 22 has a cut-out portion 28 on the side opposite to the notch 27. Another movable member 29, preferably being fixed to the centering pin 22 near its upper end and having a turned-down ear 30, is adapted to be moved in and out of the cut-out portion 28. The member 29, which will also be referred to herein as second movable means, is shown in its normal position in Figs. 3, 5 and 7. When the member 29 is moved to the position shown in Figs. 4 and 6, the turned-down ear 30 engages the wall of the second lower-most supported record at its centering aperture and moves it into supporting engagement with the notch 27.

In order to maintain the supported records in a stable, balanced position, there is connected in a suitable manner as shown in Fig. 1 at one side of the base plate 10 and beyond the pe-

riphery of the turntable 17 a hinged member 31. The hinged member 31 is shown in operative position in Fig. 2 of the drawings.

Extending from the cut-out portion 28 through the bottom of the centering pin 22 is a cam member 32. The cam member 32 is adapted to be rotated by a lever 33 which is spring-biased by a spring 34, one end of which is connected to the lever 33 and the other end of which is 10 suitably connected to the base plate 10. The movement of the lever 33 will be described hereafter. The upper end of the cam member 32 is preferably of such shape that it is in engagement with the members 25-25 and 29 at all times. When the cam member 32 is in the position shown in Fig. 5, the members 25-25 are maintained in record-supporting position and the member 29 is permitted to assume a position so that the turned-down ear 30 is out of engagement with any of the supported records. When the cam member 32 is rotated to the position shown in Fig. 6, it performs two functions. First, it moves the member 29 so that the ear 30 engages the wall of the second lower-most supported record at its centering aperture and moves it into supporting position in the notch 27. Second, it permits the members 25-25 to move to a position so that the ears 26-26 move out of record-supporting position. The upper end 30 of the cam member 32 is also provided with a notch 35. It is seen from Fig. 7 that when the cam member 32 is rotated to the position there illustrated, the notch 35 permits the member 29 to be maintained out of record-engaging position 35 at the same time that the ears 26-26 are maintained out of record-supporting position.

Driving mechanism for moving the pickup arm and operating the record-disengaging mechanism

The mechanism for moving the pickup arm 12 and for rotating the cam member 32 is best illustrated in Figs. 1 and 2 of the drawings and includes a shaft 36 which is fixed to the base plate 10 and extends downwardly therefrom. A cam wheel 37, flanged at its periphery, is mounted on the shaft 36 and is adapted to be rotated by bringing its peripheral wall into driving engagement with the peripheral wall of the driving member 19 which rotates with the turntable 17. The cam wheel 37 is brought into driving relationship with the driving member 19 by a tripping mechanism which will be described hereafter. After the cam wheel 37 has made one revolution, the driving engagement between it and the driving member 19 is broken by a cut-out portion 38 in the peripheral wall of the cam wheel 37 when it moves into a position opposite the peripheral wall of the driving member 19. One complete revolution of the cam wheel 37 defines a record-changing cycle of operation.

The first operation which the cam wheel 37 performs as it begins to rotate is to elevate the pickup arm 12 out of engagement with a record on the turntable 17. And after another record is moved to the turntable, it also lowers the pickup arm 12 into engagement with the initial playing groove of that record. The elevating and lowering of the pickup arm 12 is brought about by a cam surface 40 (Figs. 1 and 2) near the periphery of the cam wheel 37. As the cam wheel 37 rotates, the cam surface 40 is moved under a pin 41 which is adapted to be brought into and out of engagement with the underside 78 of the pickup arm 12. When the cam wheel

37 is at rest, the pin 41 rests on a portion 40C of the cam surface 40, as shown in Fig. 2. When the cam wheel 37 begins to rotate for a record-changing operation, a portion 40A of the cam surface 40 moves into engagement with the pin 41 to raise the pin and therewith the pickup arm 12. After the pickup arm 12 has been raised, the cam surface 40 maintains the pickup arm 12 in its elevated position while the cam wheel 37 is rotating to swing the pickup arm 12 to its outward-most position, to disengage the lower-most supported record to permit it to fall into playing position on the turntable 17 and to swing the pickup arm back over the initial playing groove of the new record on the turntable. Immediately after the pickup arm 12 has been swung back over the initial playing groove of a record on the turntable, a portion 40B of the cam surface 40 moves under the pin 41 and allows the pickup arm to move downwardly so that the stylus 14 in the reproducer 13 comes into engagement with the initial playing groove of a record on the turntable.

Another operation performed by the rotating cam wheel 37 is to swing the pickup arm 12 to an outward-most position after it has been raised out of engagement with a record on the turntable and then back over the initial playing groove of a record on the turntable. The pickup arm 12 has affixed to its pivotal end a tubular shaft 42 which extends downwardly through the pedestal 11. At the lower end of the shaft 42 there is affixed preferably a bifurcated lever 43 with arms 44 and 45. The free end of arm 44 has affixed to it a spring member 46. As the pickup arm 12 is moved in a horizontal plane, the spring member 46 moves over the cam areas 47-50 on the cam wheel 37. When the spring member 46 is over the cam area 47, it is not in engagement with this cam area and is adapted to move freely. When the spring member 46 is over the cam surfaces 48-50, it is adapted to engage these surfaces and thus it can only be moved against the friction created by the engagement of the spring member 46 with any of the cam surfaces 48-50. When the stylus 14 of the pickup arm 12 is in the initial playing groove of a record on the turntable 17, the lever 43 and the spring member 46 are in the positions shown in Fig. 1. As the stylus of the pickup arm 12 is moved toward the tripping groove of a record on the turntable 17, the lever 43 and the spring member 46 are moved in a clockwise direction toward a cam wall 51 on the cam wheel 37. After the rotation of the cam wheel 37 has been initiated and the pickup arm 12 has been elevated, the cam wall 51 engages the spring member 46 and moves the lever 43 and therewith the pickup arm 12 in a counter-clockwise direction until the pickup arm 12 is in its outward-most position. At the time when the pickup arm 12 has reached its outward-most position, the cam groove 49 moves into engagement with the spring member 46 and maintains the lever 43 and the pickup arm 12 in the outward-most position while the lower-most supported record is disengaged from its supports and is permitted to move into playing position on the turntable. Thereafter, the cam groove 50 moves into engagement with spring member 46 and moves the lever 43 in a clockwise direction (Fig. 1) to a position over the initial playing groove of the top record on the turntable 17. When the cam wheel 37 has stopped rotat-

ing, the spring member 46 and the arm 43 are back in the position shown in Fig. 1.

The rotating cam wheel 37 also cooperates to move the spring-biased lever 33 and the cam member 32 at the proper time to disengage a supported record from its supports so that it may drop to playing position on the turntable 17. After pickup arm 12 has been swung to its outward-most position, a finger 52 extending downwardly from the cam wheel 37 moves into engagement with the free end of the lever 33 and moves it in a clockwise direction (Fig. 1) against the biasing action of the spring 34. The clockwise movement of the lever 33 moves the cam member 32 from the position shown in Fig. 5 to the position shown in Fig. 6 to release the lower-most supported record to permit it to drop to playing position on the turntable 17. After the lower-most supported record is released, the finger 52 moves out of engagement with the lever 33 and the spring 34 moves the lever 33 and the cam member 32 back to normal position.

Automatic tripping mechanism

The automatic tripping mechanism which moves the cam wheel 37 into driving engagement with the driving member 19 includes the arm 45 of the lever 43, the free end of which is frictionally connected to a lever 53. At its frictional connection to the arm 45, the lever 53 is slotted so that it can be moved relative to the arm 45 against the force imparted thereby. Intermediate its ends, the lever 53 is slidably connected to a member 54 which extends downwardly from the bottom of the base plate 10. At the opposite end of the lever 53, there are provided a turned-down ear 55 and a turned-down ear 56. When the lever 53 is moved by the lever 43, the ear 55 is adapted to come into engagement with one end of a lever 58 which is slidably connected to the top surface of the cam wheel 37 preferably in the manner illustrated in Fig. 1. The opposite end of the lever 58 has a curved-portion 59 and a notched-portion 60, as illustrated in Fig. 1. When the lever 58 is moved by the lever 53, the curved-portion 59 and the notched-portion 60 are adapted to move into the path of a hooked-portion 61 which is provided on the member 20, which rotates with the shaft 16 and the turntable 17. When the pickup arm 12 is in the initial playing groove of a record on the turntable, the levers 53 and 58 are in the positions shown in Fig. 1. As the record is being reproduced and the stylus 14 of the pickup arm 12 is tracking the playing groove of the record, the lever 43 moves with the pickup arm 12 and moves the lever 53 into engagement with the lever 58. Thereafter, while the stylus of the pickup arm 12 is still tracking the playing groove of the record, the levers 53 and 58 are moved a predetermined distance toward the member 20 during each revolution of the shaft 16. The movement of the lever 58 a predetermined distance is sufficient to bring the curved-portion 59 but not the notched-portion 60 into the path of the hooked-portion 61 of the member 20. When the hooked-portion 61 engages the curved-portion 59, the lever 58 and the lever 53 are moved a corresponding predetermined distance in a direction opposite to that imparted by the lever 43. When the stylus of the pickup arm 12 moves into the tripping groove of the top record on the turntable, the levers 53 and 58 are moved more than a predetermined distance toward the member 20 during one

revolution of the shaft 16. The movement of the lever 58 more than a predetermined distance toward the member 20 moves the notched-portion 60 into the path of the hooked-portion 61. When the hooked-portion 61 engages the notched-portion 60, it moves the lever 58 and therewith the cam wheel 37 sufficiently to move the cam wheel 37 into driving engagement with the driving member 19. After the cam wheel 37 begins to rotate, the hooked-portion 61 moves out of engagement with the notched-portion 60 and the member 20 is of such shape that it moves the lever 58 relative to the cam wheel 37 back to the position shown in Fig. 1.

Manual tripping mechanism

In addition to the automatic tripping mechanism described, the cam wheel 37 may be moved into driving relationship with the driving member 19 by a manual control mechanism. This mechanism includes an L-shaped lever 67 pivotally connected intermediate its ends to the bottom of the base plate 10 by a pin 68 (Fig. 1). One end of the lever 67 has a turned-up portion 69 which extends through a slot in the base plate 10 and is adapted to be moved into three different positions—a manual playing position, an automatic playing position and a reject position. These positions are marked on the base plate 10, as illustrated in Fig. 1. When the lever 67 is moved to manual playing position, its opposite end moves a pin 70 which extends downwardly from the lever 33 until a curved-end 71 on the lever 67 engages the pin 70 to lock the lever 67 in manual playing position. A spring member 73, one end of which is fixed to the lever 67 and the other end of which is adapted to rest against the turned-down peripheral flange of the base plate 10, as shown in Fig. 1, is adapted to have tension created in it by a movement of the lever 67 to reject position and to have no tension created in it when the lever 67 is moved to manual playing position. Intermediate the turned-up portion 69 and the pin 68, there is affixed to the lever 67 a rod 74. The opposite end of the rod 74 is slidably connected to the base plate 10 in a suitable manner such as that shown in Fig. 1. Intermediate the ends of the rod 74, there is affixed to it a spring 75, the other end of which is fixed to base plate 10. When the lever 67 is in automatic playing position shown in Fig. 1, the spring 75 is under slight tension. However, this tension in the spring 75 is not sufficient to move the lever 67 from automatic playing position against the action of the spring 73. When the lever 67 is moved by the turned-up portion 69 to the reject position against the biasing action of the spring 73, the action of the lever 67 and the spring 75 on the rod 74 moves the notched-portion of the lever 58 into the path of the hooked-portion 61 of the member 20. When the hooked-portion 61 engages the notched-portion 60, the lever 58 and the cam wheel 37 are moved sufficiently far to bring the cam wheel 37 into driving relationship with the driving member 19. When the operator releases the turned-up end 69 after the lever 67 has been moved to reject position, the tension in spring 75 moves the lever 67 back to automatic playing position.

Mechanism for adjusting apparatus for manual operation

When the turned-up end 69 of the lever 67 is moved against the tension of spring 75 to

manual playing position, the opposite end of the lever 67 moves into engagement with the pin 70 on the lever 33, as has been previously described and rotates the lever 33 in a counter-clockwise direction until the curved-end 71 locks the lever 67 in manual playing position. The counterclockwise movement of the lever 33 rotates the cam member 32 from the position shown in Fig. 5 to the position shown in Fig. 7. As has been previously described, this movement of the cam member 31 adjusts the movable members 25—25 and 29 into a position so that the operator may drop records over the centering pin 22 into playing position on the turntable. When the lever 67 is moved into manual playing position, it also moves the free end of the rod 74 into the path of the turned-down ear 56 provided on the lever 53. In this position, the rod 74 prevents the lever 53 from engaging the lever 58 and thus operating the automatic tripping mechanism.

After a stack of records has been played and the operator desires to remove the records from the turntable, the lever 67 is moved to the manual playing position which movement, as has just been described, moves the cam member 32, and thereby the movable members 25—25 and 29 are positioned as shown in Fig. 7. With the movable members 25—25 and 29 in this position, the records on the turntable may be freely removed.

Mode of operation

The general mode of operation of the record-changing apparatus will now be described. First, the turned-up portion 69 of the lever 67 is moved to automatic playing position so that the movable members 25—25 and 29 are in the positions shown in Fig. 5. Thereafter, a stack of records 18A is placed on the centering pin 22 to be supported by the ears 26—26. In order to maintain the supported records in a stable, balanced position, the member 31 is moved to engage the top surface of the top-supported record, as shown in Fig. 2.

After the records are placed in supporting position on the centering pin 22, the driving mechanism (not shown) for rotating the turntable 17 and the driving member 19 is initiated.

Thereafter, the operator moves the lever 67 to reject position. This causes the rod 74 to move the notched-portion 60 of the lever 58 into the path of the hooked-portion 61 of the rotating member 20. The engagement of the hooked-portion 61 with the notched-portion 60 moves the lever 58 and cam wheel 37 sufficiently to bring the cam wheel 37 into driving relationship with the driving member 19.

The first function that the rotation of the cam wheel 37 performs is to swing the pickup arm 12 to its outward-most position by bringing the cam wall 51 into engagement with the spring member 46 provided on the arm 44. Thereafter, the groove 49 moves into engagement with the spring 46.

While the groove 49 is in engagement with the spring 46, the pickup arm 12 is maintained in its outward-most position and the finger 52 extending downwardly from the cam wheel 37 engages the lever 33 and moves it in a clockwise direction against the biasing action of the spring 34. The clockwise movement of the lever 33 rotates the cam member 32 from the position shown in Fig. 5 to the position shown in Fig. 6. This movement of the cam member 32 first

moves the movable member 29 outwardly to the position shown in Figs. 4 and 6 to move the second lower-most supported record horizontally into supporting position with the notch 27. Second, it permits the movable members 25-25 to move to the position shown in Figs. 4 and 6 for disengaging the lower-most supported record and permitting it to drop into playing position on the turntable 17. After the lower-most supported record has been released from the ears 26-26, the spring 34 returns the lever 33 and the cam member 32 to the position shown in Figs. 1 and 5, thus, again permitting the stack of records to be supported by the ears 26-26.

Thereafter, the cam groove 50 on the cam wheel 37 moves into guiding relationship with the spring member 46 on the arm 44. The continued rotations of the cam wheel 37 moves the lever 43 and therewith the pickup arm 12 to a position where the stylus 14 of the pickup arm 12 is over the initial playing groove of the top record on the turntable 17. Thereafter, the portion 40B of the cam surface 40 on the cam wheel 37 permits the pin 41 to move downwardly to lower the stylus 14 of the pickup arm 12 into engagement with the initial playing groove of the top record on the turntable 17.

When the stylus 14 of the pickup arm comes into engagement with the initial playing groove of the top record on the turntable 17, the cut-out portion 38 in the peripheral wall of the cam wheel 37 moves into a position opposite the peripheral wall of the driving member 19 and thereby the driving engagement between the cam wheel 37 and the driving member 19 is broken.

As the stylus 14 tracks the playing groove of a record on the turntable 17, the arm 45, frictionally connected to the lever 53, is in engagement with the lever 58 and while the stylus 14 of the pickup arm 12 is still tracking the playing groove of the record on the turntable 17, the levers 53 and 58 are moved forward and backward during each revolution of the shaft 16. These alternate movements of the levers 53 and 58 are imparted by the arm 45 and the hooked-portion 61 of the member 20, respectively. When the stylus 14 enters a tripping groove of the record on the turntable 17, the levers 53 and 58 are moved sufficiently far toward the member 20 to cause the notched-portion 60 of the lever 58 to come into engagement with the hooked-portion 61 of the member 21. Thereupon, the hooked-portion 61 moves the lever 58 and therewith the cam wheel 37 sufficiently far to bring the cam wheel 37 into driving engagement with the member 19 to be driven through another record-changing operation.

While there has been described what is at present considered the preferred embodiment of the invention, it will be obvious to those skilled in the art that various changes and modifications may be made therein without departing from the invention and it is, therefore, aimed in the appended claims to cover all such changes and modifications as fall within the true spirit and scope of the invention.

What is claimed is:

1. A record-changing apparatus comprising a centering pin, first movable means on said pin for supporting a stack of records by engaging an edge portion at the centering aperture of the lower-most supported record, a reduced-portion on said pin in the plane of the second lower-most supported record, second movable means for moving the second lower-most sup-

ported record into supporting position with said reduced portion, movable cam means for successively moving said second movable means and permitting said first movable means to move out of supporting position whereby the lower-most supported record is released from its supported position, and means for driving said cam means.

2. A record-changing apparatus comprising a fixed centering pin, first movable means on said pin for supporting a stack of records by engaging edge portions at the centering aperture of the lower-most supported record, a reduced-portion on said pin in the plane of the second lower-most supported record, second movable means associated with said pin for moving the second lower-most supported record into supporting position with said reduced-portion, cam means for successively moving said second movable means and permitting said first movable means to move out of supporting position whereby the lower-most supported record is released from its supported position, and means for driving said cam means.

3. A record-changing apparatus comprising a fixed centering pin, a pair of movable members on said pin positioned diametrically opposite thereto for supporting a stack of records by engaging edge portions at the centering aperture of the lower-most supported record, a reduced-portion on said pin in the plane of the second lower-most supported record, movable means for moving the second lower-most supported record into supporting position with said reduced-portion, cam means for successively moving said movable means and permitting said pair of movable members to move out of supporting position whereby the lower-most supported record is released from its supported position, and means for driving said cam means.

4. A record-changing apparatus comprising a tubular spindle, first movable means on said spindle for supporting a stack of records by engaging edge portions at the centering aperture of the lower-most supported record, a reduced-portion on said spindle in the plane of the second lower-most supported record, second movable means for moving the second lower-most supported record into supporting position with said reduced-portion, cam means rotatable in said spindle for successively moving said second movable means and permitting said first movable means to move out of supporting position whereby the lower-most supported record is released from its supported position, and means for driving said cam means.

5. A record-changing apparatus comprising a fixed centering pin, first movable means on said pin for supporting a stack of records by engaging edge portions at the centering aperture of the lower-most supported record, means for engaging the top-supported record for balancing the stack of records in supported position, a reduced-portion on said pin in the plane of the second lower-most supported record, second movable means for moving the second lower-most supported record into supporting position with said reduced portion, cam means for successively moving said second movable means and permitting said first movable means to move out of supporting position whereby the lower-most supported record is released from its supported position, and means for driving said cam means.

6. A record-changing apparatus comprising a fixed centering pin, a pair of movable members

portion, cam means rotatable in said spindle for successively moving said second movable means and permitting said first movable means to move out of supporting position whereby the lower-most supported record is released from its supported position, and means for driving said cam means.

15. A record-changing apparatus comprising a tubular spindle, a pair of movable members on said spindle positioned diametrically opposite thereto for supporting a stack of records by engaging edge portions at the centering aperture of the lower-most supported record, means for engaging the top-supported record for balancing the stack of records in supported position, a reduced-portion on said spindle in the plane of the second lower-most supported record, movable means for moving the second lower-most supported record into supporting position with said reduced-portion, cam means rotatable in said spindle for successively moving said movable means and permitting said pair of movable members to move out of supporting position whereby the lower-most supported record is released from its supported position, and means for driving said cam means.

16. A record-changing apparatus comprising a tubular spindle, a pair of movable members on said spindle positioned diametrically opposite thereto for supporting a stack of records by engaging edge portions at the centering aperture

5 of the lower-most supported record, means for engaging the top-supported record for balancing the stack of records in supported position, a reduced-portion on said spindle in the plane of the second lower-most supported record, movable means associated with said spindle for moving the second lower-most supported record into supporting position with said reduced-portion, cam means rotatable in said spindle for successively moving said movable means and permitting said pair of movable members to move out of supporting position whereby the lower-most supported record is released from its supported position, and means for driving said cam means.

10 17. Record-changing apparatus comprising a centering pin, first movable means on said pin for supporting a stack of records by engaging an edge portion at the centering aperture of the lowermost supported record, a reduced portion on said pin in the plane of the second lowermost supported record, a second movable means for moving the second lowermost supported record into supported position with said reduced portion, and movable cam means operatively associated with said first and second movable means 20 for successively moving said second movable means and permitting said first movable means to move out of supported position whereby the lowermost supported record is released from its supported position.

25 HARVEY C. HABEGGER.

CERTIFICATE OF CORRECTION.

Patent No. 2,287,098.

June 23, 1942.

HARVEY C. HABEGGER.

It is hereby certified that error appears in the printed specification of the above numbered patent requiring correction as follows: Page 5, second column, line 2, claim 1, strike out "movable"; and that the said Letters Patent should be read with this correction therein that the same may conform to the record of the case in the Patent Office.

Signed and sealed this 1st day of September, A. D. 1942.

(Seal)

Henry Van Arsdale,
Acting Commissioner of Patents.
